UNITED STATES PATENT OFFICE.

LOUIS F. HAGEMANN, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO.

AUTOGRAPHIC REGISTER.

Application filed December 30, 1916. Serial No. 139,809.

To all whom it may concern:

Be it known that I, LOUIS F. HAGEMANN, a citizen of the United States, residing at Niagara Falls, in the county of Niagara and 5 State of New York, have invented certain new and useful Improvements in Autographic Registers, of which the following is a full, clear, and exact description, such as will enable others skilled in the art to which 10 it appertains to make and use the same.

This invention relates to autographic registers, and with regard to its more specific features, to that type of machine in which a plurality of webs are fed over a support, 15 means being interposed between the sheets for transferring any record made upon the top sheet to the under sheets.

One of the objects of this invention is to provide a machine of the character described 20 which is stronger and less apt to get out of repair than those heretofore in use.

Another object is to provide a machine of the character described in which the web is fed over the bed in a more practical manner than heretofore.

A further object is to insure the registration of the webs with the machine and with each other in a more practical manner than heretofore.

30 A further object is to enable the webs to be more readily inserted in the machine.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

In the accompanying drawings, wherein is shown one of various possible embodiments of this invention,—

Figure 1 is a side elevation;

45 Fig. 2 is a vertical section along the line II, II, Fig. 3;

Fig. 3 is a back view section;

Fig. 4 is a view of the under side of the top plate or bed;

50 Fig. 5 is a plan view of the web gripping mechanism and associated parts;

Fig. 6 is a section along the line VI, VI, Fig. 5;

Fig. 7 is a perspective view of the roll web carriage; and

Fig. 8 is a detail section along the line VIII, VIII, Figs. 2 and 4.

Fig. 9 is a detail of the carbon roll retaining stud.

The body of the machine comprises a base 60 1 and side plates 2, the latter being held together by any suitable means, as by rods 3. The plates 2 are held to the base 1 by suitable means, as screws 4, and carry at their upper edges a bed or support 5, which may 65 be made of a separate sheet of metal having a flange at each edge which may be screwed to the side plates 2, as by screws 6.

Mounted on each side of the support 5 is a suitable housing for rolls of carbon tissue, 70 as 7 and 7, and adapted to cover said support and the housings for the rolls of carbon tissue is a cover plate 8, cut out, as shown at 9, to provide a space through which access to the web may be obtained 75 for making a record thereon. The end of the cover 8 which is toward the feeding head, later to be described, is preferably turned upwardly to form a vertical flange 9'. On the inner side of the side plates 80 are provided guides 10.

A series of web roll supports, one for each web with which it is desired to use the machine, may be joined together to form a carriage. In the embodiment of this invention illustrated, these web supports comprise U-shaped members 11 joined to strips 12 at their bases and carrying, on the free ends of the arms, means for supporting the rolls of web. This means consists of a suitable stud 13 fastened on the inside of the free ends of the arms, of a diameter preferably substantially that of the hole in the web roll. These studs may be beveled off, as at 14, on the top edge toward the U-shaped support, to facilitate the insertion of the web in place; and the arms may be made to possess sufficient resiliency to press against the ends of the rolls to prevent overrunning of the web as it is fed.

To insure that there shall be a certain minimum tension on the rolls for purposes

hereinafter to be described, tension rods 15 are provided, mounted on the ends of arms 16 which are pivoted, as at 17, to the U-shaped roll supports. These rods are adapted normally to be over the webs and to be supported by and bear laterally upon a free stretch of the web, whereby the rods will tend always to take up any slack in the webs. This carriage comprising the paper roll supports 11 and the strips 12 connecting them, is adapted to slide in and out of the main framework in the guides 10 with which the strips 12 are adapted to mate.

Mounted in the side plates 2 are suitable rods 18, one for each roll of web with which it is desired to use the machine, over which the webs are carried as they pass onto the sheet support 5. One or more of these rods may be made removable, as by slotting the bearing at one end thereof, as shown at 19. Journalled in the side plates 2 is an oscillatory hand-operated driving shaft 20 carrying, at its outer end, an operating handle 21. Rigidly attached to the driving shaft are driving arms 22. Pivotaly connected to the driving arms, as at 23, and connecting them to the operating bar 27, about to be described, are arms 24.

The feeding mechanism comprises a reciprocating carriage 25 adapted to slide in suitable guideways 26 on the under side of the web support. Slidingly mounted upon this reciprocating carriage 25 is a reciprocatory operating bar 27 which is attached by a suitable cross rod 28 to the inner end of the arms 24.

Suitable blocks 29 on the reciprocating carriage and a stop block 30 upon the operating rod 27 are adapted to engage and limit the movement of the operating rod inward relative to the sliding carriage. Also by engagement of the blocks 29 and 30 the carriage is coupled to move inward with the operator bar after a predetermined amount of movement of the latter relative thereto. During this relative movement the operating bar 27 and the carriage 25 are operatively disconnected. The blocks 29 and a similar set 29' also on the reciprocating carriage, but on the other end of the operating bar 27, serve as guides for the operating bar. These blocks 29 and 29' may have projecting fingers 31 engaging grooves in the operating bar 27 to retain the latter in place (see Fig. 8.)

Mounted upon the opposite end of the sliding frame from the cross rod 28 is a gripper head 32 adapted normally to embrace the web, and serve as a gripper jaw, and comprising a head piece 33, to one side of which is pivoted, as at 34, a tearing bar 35, and the other side of which carries a suitable spring catch 36 for engaging a recess in the free end of the tearing bar. Mounted upon the head piece 33 are spring fingers 38 normally lying substantially flush with the upper surface of the head piece 33; and piv-

otally mounted, as at 39, upon the head are operating fingers 40, preferably one for each spring finger used. These operating fingers have one end 41 adapted to be engaged by the operating bar 27, as by means of a pin 42 70 on the operating rod and slots 43 in the operating fingers. In this wise the fingers 40 couple the operator bar with the carriage to effect advance movement of the latter after a predetermined amount of relative movement. The other end of each of the operating fingers carries a cam surface 44 adapted to engage spring fingers 38 and press the same upwardly toward the tearing bar 35 to grip the web when the operating fingers are 80 rotated by a relative movement of the operating rod to the reciprocating carriage.

From the construction described it will be evident that, since the reciprocating carriage 25 is operated by the operating bar 27, during which movement the bar and carriage move together, and since the gripper head 32 is operated to grip the paper, by movement of the operating bar 27 relative to the reciprocating carriage, it is desirable that some 90 means be provided for restraining movement of the reciprocating carriage until the required amount of movement of the operating bar has taken place.

To accomplish this, catches 45 and 45' may 95 be mounted upon the reciprocating carriage in position to engage notches 46 and 46' in the guideways, and springs 47 and 47' are provided, tending to press the catches in a direction to engage said notches. The catch 100 45 is so positioned as to engage notch 46 when the carriage is in its extreme inward position, and the catch 45' is adapted to engage the notch 46' when the carriage is substantially in its extreme extended position. 105

In order to permit the movement of the reciprocating carriage after there has been the required amount of relative movement between the operating rod and the reciprocating carriage, the inner end of each of the catches 45 and 45' is provided with a tripping arm 48 and 48', and means are provided upon the operating rod to engage said tripping arms to release the reciprocating carriage. By properly positioning the catch 110 45 and its corresponding notch 46, the block 30 used to limit the inward movement of the operating rod relative to the carriage may also be used to trip the catch 45. The means for tripping the catch 45' may conveniently 115 be a block 49 attached to the operating rod, so positioned as to trip the catch after a limited retraction of the operating rod relative to the reciprocating carriage.

In machines of this character, in which the 120 webs may carry printed sales forms thereon, it is desirable that the feed of the web be of such length that the printed forms will appear in their proper place successively on the writing space of the machine. In order 125 130

adjustably to limit the feed, a suitable lug 50 may be provided on the driving shaft 20 carrying, in a threaded opening 51 therein, an adjusting screw 52 having a knurled head 53 adapted to engage the base of the machine 1, as at 54, when the desired feed has been made.

A fixed adjustment of feed, however, does not in itself always maintain the position of the printed forms in proper position, due, perhaps, to stretching and shrinking of the paper caused by differences in tension and atmospheric conditions. Furthermore, where a plurality of webs are fed, the adjustment of feed which is correct for the upper or visible web may not be correct for the under or hidden webs, whereby the forms on the several webs get out of register with each other.

In order to insure the continual registration of the forms on the webs with each other and with the writing space on the machine, it is desirable to adjust the position of the web relative to the forms themselves. This is conveniently done by providing a series of physical alterations in the webs, in fixed relation to the forms printed thereon, and means for adjusting the position of the forms by engagement with these physical alterations. The form of physical alteration employed in the embodiment illustrated consists of apertures or perforations through the webs, and the form of adjusting means consists of pins adapted to engage these alterations.

The means for operating these pins is as follows:

Attached to the under side of the support 5 are brackets 55 in which is pivoted a shaft 56. Slidably mounted upon the shaft 56 is a block 57, preferably of a fibrous material, which is splined to the shaft, as at 58. Rotatably mounted upon the shaft 56 and frictionally retained between the fibrous block 57 and a collar 59, is a gear 60. Also attached on the shaft 56 are suitable collars 61 and 62 for a purpose about to be described, and a suitable spring 63 bearing against one of said collars presses the fibrous block 57 against the gear. In order to increase the friction between the fibrous block and the gear, they may be provided with mating cone surfaces, as shown at 64.

The under side of the operating rod 27 is provided at each end, as at 65 and 66, with rack teeth, adapted to engage with the teeth of the gear 60, while its central portion 67 is preferably smooth, being devoid of such teeth. The gear 60 is mutilated by having a portion of the teeth cut away, as shown at 68, to provide a smooth surface adapted to slide upon the central portion of the operating rod, whereby, at each extreme of the movement of the reciprocating carriage, the gear and rod are operatively connected, hay-

ing a rack and pinion engagement, whereas during the entire central portion of the movement of the reciprocating carriage, the gear remains stationary, the bar 27 and shaft 56 being operatively disconnected.

Fastened to the under side of the support are vertical guides 69 in which reciprocate web controlling fingers or adjusting pins 70; and fastened to the collars 61 and 62 are operating pins 71 adapted to engage slots 72 in the sides of the adjusting pins 70 to reciprocate said pins vertically in their guides as the shaft 56 is rotated to right or left by the gear 60. In alignment with the top of the guides 69 there is formed in the support, suitable holes 73, to enable the guide pins to extend upwardly above the support. Mounted upon the flange 9' of the cover 8 there may be provided guide fingers 74 having openings in registry with the openings in the bed plate to retain the web in place as the pins project upwardly. To facilitate the entry of the adjusting pins into the perforations in the sheets, they are preferably provided with tapered or conical ends 75 which tend to center the perforations over the pins, thereby adjusting the sales forms. It is however, more practical to perform the slight movement of the sheets necessary to adjust the position, contrary to the direction of feed rather than in the direction thereof, because the normal tension on the web assists in the former case and resists in the latter. For this reason the axis of the conical ends on the pins is preferably not coincident with the axis of the pins but is spaced therefrom in the direction of feed. With this construction, by adjusting the feed to make it a slight amount more than the distance between successive forms on the webs, the conical ends on the pins may enter the perforations substantially centrally thereof. Thereafter, when the web is released by the gripper head, there will be a slight retrograde movement of the web until the pins themselves are central of the perforations.

The sides of the pins may be flattened, as at 76, slightly, if desired, to facilitate the entry of the pins through the plurality of webs even though the perforations be laterally slightly out of alignment.

Mounted also upon the vertical flange 9' is a spring finger 77 adapted to lie normally free from and above the web. This spring finger is so shaped, as shown in Fig. 2, that when the reciprocating head has been retracted to the extreme position the inside of the tearing bar 35 will engage the spring finger 77 and cause the same to press downwardly and grip the web to the bed plate.

In order to facilitate the insertion of the rolls of carbon paper in the housings 7, there is provided, centrally of one end, a stud 78, and central of the other end a spring-pressed

70

4
stud 79 carrying at its inner end a flattened portion 80 for engagement with a corresponding recess in the roll. This spring-pressed stud may consist of a collar 81 extending 5 outwardly from the end of the housing and a central stud 82 extending inwardly through said collar and carrying at its outer end an operating handle 83, said collar providing a housing for a spring 84 adapted to 10 engage a shoulder 85 on the inner side of the collar and a shoulder 86 on the stud, whereby the stud is pressed inwardly relative to said collar.

A suitable catch, as the spring finger 87 15 and the pin 88, may be provided for holding the cover on the support, and a suitable finger 89 adapted to engage one of the rods 3 may be provided to latch the roll supporting carriage in proper position.

20 The operation of this machine is as follows: Suitable rolls of web having record blanks printed thereon, and preferably having a series of perforations bearing a fixed relation to the record blank, are inserted in 25 place upon the studs 13 of the roll supporting carriage and carried underneath the tensioning rods 15. The roll supporting carriage is thereupon slid into the body of the machine, the free ends of the webs extending 30 outwardly of the machine. The cover 8 of the machine having been lifted, the webs are carried over the bed of the machine, each over its corresponding rod 18 until the 35 openings in the sheet are positioned over the adjusting pins and over the reciprocating head, the tearing bar being raised, and the reciprocating carriage being in retracted position. As each web is inserted in place upon the support the corresponding carbon sheet 40 will be placed thereover and fed onto the opposite roll. The cover 8 may now be secured in place, and the tearing bar 35 thrown over the web and caught onto the catch 36. The machine will then be in operating 45 position, and any record which is written upon the upper sheet will, by means of the carbon sheets, be transferred to the lower sheets. When it is desired to feed a new set of sheets into the machine, the operating 50 handle will first be turned in a counter-clockwise direction. The first portion of this movement will cause a relative movement between the operating bar 27 and the reciprocating carriage which will cause through 55 the medium of the operating fingers 40, the spring fingers 38 to press the web up against the tearing bar, thereby clamping the ends of the webs in the reciprocating head and coupling the operator bar with the sliding 60 carriage. Simultaneously, since the teeth of the gear 60 are in engagement with the teeth of the rack 65 on the end of the operating rod, the said movement of the operating rod will rotate the shaft 56 and cause the withdrawal 65 of the pins 70 below the level of the

support. A continued movement of the handle is then made in the counter-clockwise direction as far as it will go, carrying with it the web, and at the last end of the stroke when the inner series of rack teeth comes 70 into engagement with the teeth of the gear, the pins being already in their lowermost position, no further rotation of the shaft in the same direction is possible, so that the rotation of the gear by the rack is accompanied by a slipping of the friction clutch. 75

The handle is then turned in the reverse direction. As soon as the reverse movement is started, the relative movement between the operating rod and the reciprocating carriage operates the operating fingers 40 to cause the spring fingers 38 to release the web, and simultaneously the engagement of the gear 60 with the rack 66 will rotate the shaft 56 to cause the pins 70 to project 80 upwardly through the sheet, the perforations in which will, when the machine is in proper adjustment, be substantially over these pins. Also this reverse of the hand operated member positively retracts the operator bar relative to the carriage 25 until the stop or coupling member 30 meets the stop or coupling member 29. Upon continued clockwise movement of the operating rod the head piece 33 and tearing bar 35 slide over the web, which is retained in place by the pins 70. 85

90 When, however, the head has reached its extreme retracted position, the inner edge of the tearing bar 35 will engage the spring finger 77 to press the webs against the support to hold them in place. 100

When the next sheet is ready to be fed, the operating handle is again moved in a counter-clockwise direction and the above 105 cycle is repeated.

110 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 115

120 It is also to be understood that the language used in the following claims is intended to cover all of the generic and specific features of the invention herein described, and all statements of the scope of the invention, which, as a matter of language, might be said to fall therebetween.

125 Having described my invention, what I claim as new and desire to secure by Letters Patent, is:—

130 1. A device of the character described comprising, in combination, a support, means for feeding a web comprising a reciprocating member, means for reciprocating said member comprising a driving shaft,

spaced driving arms on said shaft, arms connecting said reciprocating member to said driving arms, and a carriage having web roll supports movable into and out of said frame, between the planes of movement of said spaced arms.

2. A device of the character described comprising, in combination, a web support, reciprocating means for feeding a web relative to said support, means for adjusting the position of a portion of said web relative to said support comprising a member movable into and out of engagement with the web, and means including a friction clutch 10 for operating said member, said last mentioned means being connected to for movement by the feeding means only when the feeding means is in an extreme position of travel.

20 3. A device of the character described comprising, in combination, a support for a web, means for feeding said web relative to said support, comprising a member adapted alternately to grip and release said web, 25 means adapted to engage said web to retain a portion thereof in predetermined position relative to said support while released from said gripping member, and means adapted to hold said engaging means in predetermined 30 position during a certain portion of the motion of the feeding means regardless of the direction of movement thereof.

4. A device of the character described comprising, in combination, a support for a web, 35 means for feeding said web relative to said support, comprising a member adapted alternately to grip and release said web, means adapted to engage said web to retain a portion thereof in predetermined position relative to said support while released from said gripping member, comprising pins adapted to extend through perforations in said web, and means adapted to hold said pins in predetermined 40 position during a certain portion of the motion of the feeding means regardless of the direction of movement thereof.

5. A device of the character described comprising, in combination, a support for a web, reciprocating means for moving a web relative to said support, means movable into and out of engagement with the web for adjusting the position of said web relative to said support, means for operating said 50 adjusting means comprising an operating rod adapted to be operatively connected to said reciprocating feeding means, said operating rod having a rack portion and a smooth portion and a gear operatively connected to said adjusting means having teeth adapted to engage said rack portion of said operating rod, and a mutilated portion adapted to engage said smooth portion of said operating rod whereby said adjusting means is operated only while the rack portion of said operating rod is in engagement with the gear and is retained in position while the smooth portion of said operating rod slides on the mutilated portion of the gear, and a friction clutch interposed between said gear and said adjusting means.

6. A device of the character described comprising, in combination, a support for a web, reciprocating means for moving a web relative to said support, means movable into and out of engagement with the web for adjusting the position of said web relative to said support, means for operating said adjusting means comprising an operating rod adapted to be connected to said reciprocating feeding means, said operating rod having a rack portion and a smooth portion, and a gear operatively connected to said adjusting means having teeth adapted to engage said rack portion of said operating rod, and a mutilated portion adapted to engage said smooth portion of said operating rod whereby said adjusting means is operated only while the rack portion of said operating rod is in engagement with the gear and is retained in position while the smooth portion of said operating rod slides on the mutilated portion of the gear.

7. A device of the character described comprising, in combination, a support for a web, reciprocating means for moving a web relative to said support, means movable into and out of engagement with the web for adjusting the position of said web relative to said support, means for operating said adjusting means comprising an operating rod adapted to be operatively connected to said reciprocating feeding means, said operating rod having a rack portion and a smooth portion, a gear operatively connected to said adjusting means having teeth adapted to engage said rack portion of said operating rod, and a mutilated portion adapted to engage said smooth portion of said operating rod whereby said adjusting means is operated only while the rack portion of said operating rod is in engagement with the gear and is retained in position while the smooth portion of said operating rod slides on the mutilated portion of the gear, and means for reciprocating said reciprocating means comprising a driving shaft, driving arms connected to said shaft, and means for connecting said driving arms to said operating bar.

8. A device of the character described comprising, in combination, a support for a web, reciprocating means for moving a web relative to said support, means movable into and out of engagement with the web for adjusting the position of said web relative to said support, means for operating said adjusting means comprising an operating rod adapted to be operatively connected to said reciprocating feeding means, said operating rod having a rack portion and a smooth portion, a gear operatively connected to said adjusting means having teeth adapted to engage said rack portion of said operating rod, and a mutilated portion adapted to engage said smooth portion of said operating rod whereby said adjusting means is operated only while the rack portion of said operating rod is in engagement with the gear and is retained in position while the smooth portion of said operating rod slides on the mutilated portion of the gear, and a friction clutch interposed between said gear and said adjusting means.

9. A device of the character described comprising, in combination, a support for a web, reciprocating means for moving a web relative to said support, means movable into and out of engagement with the web for adjusting the position of said web relative to said support, means for operating said adjusting means comprising an operating rod adapted to be operatively connected to said reciprocating feeding means, said operating rod

- having a rack portion and a smooth portion, a gear operatively connected to said adjusting means having teeth adapted to engage said rack portion of said operating rod and 5 a mutilated portion adapted to engage said smooth portion of said operating rod whereby said adjusting means is operated only while the rack portion of said operating rod is in engagement with the gear and is retained 10 in position while the smooth portion of said operating rod slides on the mutilated portion of the gear, and a friction clutch interposed between said gear and said adjusting means, and means for reciprocating 15 said reciprocating means comprising a driving shaft, driving arms connected to said shaft and means for connecting said driving arms to said operating rod.
9. A device of the character described 20 comprising, in combination, a web support, means for feeding a web relative to said support, including a movable tearing bar, means for moving said tearing bar longitudinally of said support and means operable 25 by said moving means for automatically clamping said web against said tearing bar upon movement of the tearing bar.
10. A device of the character described 30 comprising, in combination, a support for a web, means for feeding a web relative to said support comprising a movable member constantly embracing said web, means for moving said member longitudinally of said support, and means operable by said moving 35 means for automatically tightening said means for embracing to grip said web upon movement of said member.
11. A device of the character described 40 comprising, in combination, a support for a web, means for feeding a web relative to said support comprising a member constantly embracing said web, means for moving said member longitudinally of said support, and means operable by said moving means for 45 tightening said embrace to grip said web, said member including a tearing bar.
12. A device of the character described 50 comprising, in combination, means for feeding a web relative to said support comprising a reciprocating head below said web, and a tearing bar pivoted to said head at one end, the other end being free and adapted to lie above said web, means for locking the free end of said tearing bar to said head 55 and means for pressing the web against the tearing bar.
13. A device of the character described 60 comprising, in combination, a support, means for feeding a web relative to said support comprising a reciprocating head below said web, a tearing bar pivoted to said head at one end, the other end being free and adapted to lie above said web, means for locking the free end of said tearing bar to 65 said head, and means for pressing the web against the tearing bar, comprising spring fingers on the head, and an operating finger pivoted to said head adapted to press said spring fingers toward said tearing bar.
14. A device of the character described 70 comprising, in combination, means for feeding a web relative to said support comprising a reciprocating head below said web, a tearing bar pivoted to said head and adapted to lie above said web, means for locking 75 the free end of said tearing bar to said head, means for pressing the web against the tearing bar comprising spring fingers on the head, an operating finger pivoted to said head adapted to press said spring fingers toward said tearing bar, and a spring finger connected to the support and adapted to be engaged by said tearing bar to clamp the web to the support.
15. A device of the character described 80 comprising, in combination, a support for a web, means for engaging said web to feed the same including a member adapted normally to lie over said web, said member being movable from a position over said web 85 to a position clear of the web to expose the same.
16. A device of the character described 90 comprising, in combination, a support for a web and means for feeding a web relative to said support comprising a member constantly partially embracing said web, a member capable of movement from a position to complete the embracing of said web 95 to a position clear of the web to expose the same, and means to tighten said embrace to grip the web.
17. A device of the character described 100 comprising, in combination, means for feeding a web comprising a member adapted to grip and release the end of the web, and means operated by said gripping member for retaining the web in place while said member is being actuated to grip the sheets.
18. A device of the character described 105 comprising, in combination, a support for a web, means for feeding a web comprising a member adapted to grip and release the ends of the web, and a spring finger connected to said support in position to be engaged by said gripping member to retain the web in place while said member is being actuated to grip the sheets.
19. A device of the character described, 110 comprising in combination, a support for sheets to be fed, means for feeding said sheets relative to said support, and means for holding said sheets in position preparatory to being fed by said feeding means, said holding means being movable from a position in which it may be caused to engage said sheets to a position clear of said sheets 115 to expose the same.

20. A device of the character described, comprising in combination, a support for sheets to be fed, means for feeding said sheets relative to said support and means for holding said sheets in position preparatory to being fed, a removable cover for said support, said holding means being attached to said cover, whereby when said cover is in place said holding means will be in a position in which it may be caused to engage said sheets, and when said cover is removed the holding means will be in a position clear of said sheets to expose the same. 70
- 5 21. A device of the character described, comprising in combination, means for feeding a web comprising a reciprocating member including a gripper for alternately gripping and releasing said web, a part for operating said gripper having a limited movement relative to and operatively disconnected from said reciprocating member, said gripper being adapted to be operated by said relative movement, means for operatively connecting said part and said member, 75
- 10 22. A device of the character described comprising, in combination, means for feeding a web comprising a reciprocating member including a gripper for alternately gripping and releasing said web, a part for operating said gripper having a limited movement relative to and operatively disconnected from said reciprocating member, said gripper being adapted to be operated by said relative movement, and means for operatively connecting said part and said member, 80
- 15 23. A device of the character described comprising, in combination, means for feeding a web comprising a reciprocating member including a gripper for alternately gripping and releasing said web, a part for operating said gripper having a limited movement relative to and operatively disconnected from said reciprocating member, said gripper being adapted to be operated by said relative movement, means for operatively connecting said part and said member at each end of its limited relative movement, 85
- 20 24. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, and means adapted operatively to connect said holding means to said feeding means at predetermined positions in the feeding motion. 90
- 25 25. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, means adapted operatively to connect said holding means to said feeding means at predetermined positions in the feeding motion. 95
- 30 26. A device of the character described comprising, in combination, a support for a web, means for feeding said web relative to said support, means adapted to engage said web to hold a portion thereof in predetermined position relative to said support, means adapted to cooperate with said engaging means to hold said web in position to be engaged thereby, said cooperating means being adapted to be moved from a position to cooperate with said engaging means to a position free from the web to expose the same, said feeding means being adapted normally continually to embrace said web and having a portion movable from embracing position to a position free from said web to expose the same. 100
- 35 27. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, and means adapted operatively to connect said holding means to said feeding means at predetermined positions in the feeding motion. 105
- 40 28. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, means adapted operatively to connect said holding means to said feeding means at predetermined positions in the feeding motion. 110
- 45 29. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, and means adapted operatively to connect said holding means to said feeding means at predetermined positions in the feeding motion. 115
- 50 30. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, means adapted operatively to connect said holding means to said feeding means at predetermined positions in the feeding motion. 120
- 55 31. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, means adapted operatively to connect said holding means to said feeding means at predetermined positions in the feeding motion. 125
- 60 32. A device of the character described comprising, in combination, a support for a web, means for feeding said web relative to said support, comprising a member adapted normally continually to embrace said web and having a portion thereof movable from embracing position to a position free from said web to expose the same, means adapted to engage said web to retain a portion thereof in predetermined position relative to said support, means adapted operatively to connect said holding means to said feeding means at predetermined positions in the feeding motion. 130

feeding motion, and means adapted to co-operate with said engaging means to retain the web in position to be engaged thereby, said means being movable to a position free from said web to expose the same.

29. A device of the character described comprising, in combination, a support for a web, means for feeding said web relative to said support, comprising a member adapted 10 normally continually to embrace said web and having a portion thereof movable from said embracing position to a position free from said web to expose the same, means adapted to engage said web to retain a portion 15 thereof in predetermined position relative to said support, means adapted operatively to connect said holding means to said feeding means at predetermined positions in the feeding motion, means adapted to co-20 operate with said engaging means to retain the web in position to be engaged thereby, and means for retaining the web in place while it is being engaged by said engaging means, said retaining means and said cooperating means being movable to a position 25 free from said web to expose the same.

30. In a device of the character described, in combination, means adapted to feed web supplies so that succeeding portions of one 30 web shall occupy superposed relation to succeeding portions of another web, permitting manifolding recording, comprising a reciprocatory gripper, a sliding frame to which said gripper is fixed, a reciprocatory bar 35 adapted to reciprocate said frame and movable relative thereto, means carried by said frame adapted to open and close said gripper, stationary catches spaced apart longitudinally of the line of feed, a plurality of 40 latches carried by said sliding frame adapted to engage said catches, respectively, at different times, and means operated by relative movement between said frame and bar adapted to release said latches, the one by 45 said relative movement in one direction, and the other by said relative movement in the opposite direction, said opening and closing means being operably connected to said bar to be operated by relative movement between 50 said bar and frame.

31. In a device of the character described, in combination, means adapted to feed web supplies so that succeeding portions of one web shall occupy superposed relation to succeeding portions of another web, permitting 55 manifolding recording, comprising a reciprocatory gripper, a sliding frame to which said gripper is fixed, a reciprocatory bar adapted to reciprocate said frame and movable relative thereto, means carried by said frame adapted to open and close said gripper, a stationary catch, a latch carried by 60 said frame adapted to engage said catch and prevent movement of said frame in one direction, means operated by relative movement between said bar and frame adapted to close said gripper and release said latch from said catch after the close of said gripper preliminary to the feed movement of the 65 web, a driving shaft, a crank connected thereto and a link connecting said crank and reciprocatory bar.

32. In a device of the character described, in combination, means adapted to feed a web at intervals comprising a reciprocatory gripper, a web controlling finger, means whereby said finger is moved into and out of an aperture in the web between the intervals of advance of the web comprising a reciprocatory operator bar movable relative to 75 said gripper, means adapted to couple said bar with said gripper to retract the latter with the former after a predetermined amount of relative retractive movement 80 therebetween, means whereby the retractive movement of said bar relative to said gripper effects engagement of said finger with said aperture, and an oscillatory hand-operated member to reciprocate said operator bar, said coupling means being such as to require reverse movement of said hand-operated member to effect said relative retractive movement to effect said engagement.

In testimony whereof I affix my signature, in the presence of two witnesses.

LOUIS F. HAGEMANN.
